UNITED STATES PATENT OFFICE.

SAMUEL KOFF, OF BROOKLYN, NEW YORK.

BOX CONSTRUCTION.

1,119,085.

Specification of Letters Patent.

Patented Dec. 1, 1914.

Application filed May 2, 1914. Serial No. 835,816.

To all whom it may concern:

Be it known that I, SAMUEL KOFF, a citizen of the United States, residing at Brooklyn, in the county of Kings and State of New York, have invented certain new and useful Improvements in Box Construction; and I do hereby declare the following to be a full, clear, and exact description of the invention, such as will enable others skilled in the art to which it appertains to make and use the same.

This invention has for its object to provide a paper or cardboard receptacle which shall be simple and inexpensive in construction and efficient, strong and durable in use.

With this and other objects in view, the invention consists in the construction, formation and arrangement of parts hereinafter more specifically described, claimed and illustrated in the accompanying drawing, in which,

Figure 1 is a perspective view of the complete box. Fig. 2 is a diametrical vertical sectional view therethrough, and Fig. 3 is a horizontal sectional view therethrough.

Referring to the drawing, the numeral 5 indicates the body or side wall of the receptacle which is here shown circular but which may be constructed in any preferred shape, as will be understood. The bottom edge 6 of the body 5 is turned inwardly at right angles thereto as clearly indicated in Fig. 2, and this bending is preferably accomplished by moistening and subsequently bending the edge and retain it in such position until thoroughly dry. The bottom 7 is shaped in conformity with the body 5 and is secured to the inturned flange or edge 6 by suitable staples or the like 8.

40 The cover 9 is bent downwardly on a line representing the shape of the body 5 to form the depending edge 10. A band 11 encloses or surrounds the depending edge 10

of the cover 9 and is suitably secured thereto by staples 12. The overlapped ends 13 and 14 of the band 11 and the body 5 are secured together by suitable staples 15 secured therethrough. The band 11 is formed with a plurality of spaced openings 16 adjacent the lower edge of the depending edge 10 and receive therethrough the tongues or extensions 17 formed integral with said edge 10. Suitable staples 18 are positioned through the tongues 17 and band 11 for securing these parts together.

In use, the band 11 telescopically receives the body 5 as clearly shown in Fig. 5, and the band 11 is materially increased in strength in the plane of the upper edge of the body 5 by the reinforcing tongues 17 of the cover 9.

As clearly shown in Fig. 3, the inturned edge 6 of the body 5 is not cut, neither is the depending edge 10 of the cover 9, and this is a very important feature of my invention caused by forming these parts solid and uncut the strength of the box is materially increased.

What I claim is:

A receptacle comprising a body having an inwardly turned edge, a bottom secured to said edge, a cover having a depending edge extending at right angles thereto and tongues formed integral with said depending edge, a band secured to said depending edge and having openings therein receiving said tongues, and means for securing said tongues on the outside of said band.

In testimony whereof I have signed my name to this specification in the presence of two subscribing witnesses.

SAMUEL KOFF.
